ATTACHMENT FOR PISTONS FOR INTERNAL COMBUSTION ENGINES

Walter M. Howser, Anderson, Ind., assignor to William H. Forse, Anderson, Ind.

Application December 21, 1937, Serial No. 181,048

2 Claims. (Cl. 309—12)

This invention relates to certain new and useful improvements in attachment for pistons for internal combustion engines.

The primary object of this invention is to provide means within the piston of an internal combustion engine for engaging the walls of the working cylinder thereby preventing excessive vibration of the piston within the cylinder and preventing the resultant sound produced by what is known in the art as "piston slap."

A further object of this invention is to provide a device of the above mentioned character which includes a spring bent to form curved arm portions connected by a curved intermediate portion shaped to conform to the inner wall of the engine cylinder.

A still further object of this invention is to provide a device of the above mentioned character comprising a spring or resilient member bent in such a manner as to avoid contact with the wrist pin bosses and out of the path of the connecting rod during operation of the engine.

Other objects and advantages of the invention will become apparent during the course of the following description, taken with the drawings, and wherein:

Figure 1 is a vertical cross-sectional view of an internal combustion engine illustrating an embodiment of the invention as applied thereto;

Figure 2 is a transverse cross-sectional view taken on line 2—2 of Figure 1, looking in the direction of the arrows, illustrating the contour of the spring member and showing the manner in which the ends extend through the piston wall in openings which are present in many of the pistons employed in present-day motor cars;

Figure 3 is a perspective view of the spring device showing the same greatly enlarged to illustrate the details thereof;

Figure 4 is a horizontal cross-sectional view of an engine piston illustrating a modified form of the invention as applied thereto;

Figure 5 is a vertical fragmentary cross-sectional view of an engine piston showing the expansion or spring device mounted above the wrist pin bosses;

Figure 6 is a plan view of the modified form of the invention showing the same detached from the piston;

Figure 7 is a vertical cross-sectional view of another modified form of the invention;

Figure 8 is a horizontal cross-sectional view taken on line 8—8 of Figure 7, looking in the direction of the arrows;

Figure 9 is a top plan view of the spring de-

vice used in Figures 7 and 8, illustrating the details of construction; and

Figure 10 is a still further modified form of the invention showing the same applied to a conventional piston construction.

In the drawings, wherein for the purpose of illustrating the invention and wherein like reference characters will be employed to designate like parts throughout the same, the reference character 5 will generally be employed in Figures 10 to 3 inclusive to represent a piston having a head portion 6 and the usual piston rings 7.

The piston 5 also includes a skirted portion 8 having opposite bosses 9 for receiving a wrist pin 10. In pistons of this type wherein an expansion skirt 8 is provided, slots 11 are formed between the juncture of the piston head and the skirt to allow for expansion and contraction.

The invention comprises an expansion spring 12 including curved arm portions 13 connected by an arcuately curved portion 14 while the free ends as at 15 are slightly bent in order to hook into one of the slots 11. Offset portions 16 are interposed between arcuately curved portion 14 and the curved arms 13 to allow the curved portion 14 to extend through the opposite slot 11 of the piston skirt and engage the inner cylinder wall.

It will be noted that the bent free ends 15 do not extend clear through the slot 11 and do not engage the cylinder wall as this would result in scoring thereof and engine compression losses.

It is to be noted that the expansion spring device 12 is curved in such a manner so as not to obstruct the movement of the connecting rod and will not touch any part of the piston between its ends, thereby preventing rattling or vibration sounds.

In Figures 4 to 6 inclusive, the modified form of the invention comprises a piston 5' having a head portion 6' and the usual piston packing rings 7'. The head portion 6' is provided with a skirt 8' similar to the piston shown in Figs. 1 and 2 and is also provided with wrist pin bosses 9'.

Slots 11' are formed between the skirt 8' and head portion 6' in the usual manner, also similar to Figs. 1 and 2.

The modified form of the invention includes a pair of parallel spring arms 13' connected at one end by an arcuately curved portion 14' which connects the parallel spring arms 13' by means of offset portions 16'. The free ends of the spring arms 13' are bent away from each other as at 15' and are provided with foot portions 17' adapted to contact the cylinder wall at spaced apart joints.

It will be noted that the arcuately curved portion 14' is adapted to enter one of the slots 11' and extend therethrough a short distance so as to engage the cylinder wall and hold the piston in a true vertical plane. The opposite end of the spring arms 13' engage the cylinder walls at the points 17' to further aid in maintaining the piston parallel with the sides of the cylinder wall during operation of the engine. It will be noted that the cylinder wall engaging portions 17' also assist in centering the spring device by reason of the fact that they engage the ends of the slots 11' to prevent the rotation of the spring device relative to the piston.

15 It is also to be noted that the parallel spring arms 13' are slightly bowed when viewed from a horizontal direction as in Fig. 5 in order to add to the resiliency supplied by the outwardly bent free end portion 15'.

20 In Figs. 7 to 9 inclusive, a piston 5'' is provided with a head 6'' having the usual packing rings 7'' to prevent loss of compression. The head 6'' is provided with a split skirt portion 8'' having slots 11'' similar to the slot shown in Figs. 1 and 5. A wrist pin 10'' is carried by the piston skirt in suitable opposed bosses for supporting a connecting rod 25'' having a bearing 26''. The invention comprises, in its modified form, opposite curved spring members 13'' connected at one end as at 14'' adapted to engage the inner wall of the piston skirt 8'' to expand and urge the piston toward one wall of the cylinder in which the piston reciprocates. The opposite curved spring members 13'' have their free ends 15'' curved inwardly and bent as at 16'' to form meeting foot members 17''. When the spring is in position as shown in Fig. 7 the foot portions 17'' embrace the connecting rod 25'' and assist in forcing the piston toward one wall of the cylinder.

35 In the other modified form of the invention, the piston 5''' is provided with a head 6''' and the usual packing rings 7'''. A skirt 8''' is connected to the head 6''' at opposite points, leaving slots 11''' for the purpose of expansion and contraction of the skirt 8'''. The skirt is provided

with a wrist pin 10''' in the same manner as the piston shown in the above described figures and is adapted to support a connecting rod 25''' by means of a wrist pin bearing 26'''.

5 Formed on the connecting rod 25''' is a boss 27''' adapted to receive one end of a coil spring 28''' so that the opposite end thereof will be seated upon and engage a boss 29''' formed on the inner wall of the piston skirt 8'''.

10 In this construction, the spring 28''' will urge the piston skirt 8''' into engagement with the cylinder wall in which the piston reciprocates and will prevent piston slap, resulting from undersized pistons or worn cylinders.

15 It is to be noted that the form of the invention herewith shown and described is to be taken as the preferred embodiment of the same and that various changes in the shape, size and arrangement of parts may be resorted to without departing from the spirit and scope of the invention as claimed.

I claim:

1. In combination with a hollow piston having circumferentially extending opposite slots in the side wall thereof, an expansion spring member having its ends mounted in said slots, one of said ends terminating inwardly of the outer face of the hollow piston and the other of said ends being curved and extending through the slot beyond the outer face of the hollow piston for engagement with the wall of a cylinder for centering the piston during its reciprocal movements.

2. In combination with a hollow piston having opposite circumferentially extending arcuate slots in the side wall thereof between the head and skirt portions, an expansible spring member comprising a pair of parallel arms connected at corresponding ends by an arcuately curved portion adapted to extend through one of the slots for contact with a cylinder wall and anchor portions for the spring member formed on the other ends of the parallel arms adapted to be seated in the opposite slot and disposed inwardly of the outer face of the head and skirt.

45 WALTER M. HOWSER.
